Attleboro

UNITED STATES PATENT OFFICE.

WOLFGANG HERMANN, OF CHICAGO, ILLINOIS, ASSIGNOR TO METAL SPECIALTIES MANUFACTURING COMPANY, OF CHICAGO, ILLINOIS, A CORPORATION OF ILLINOIS.

DASH LAMP.

Application filed January 16, 1926. Serial No. 81,753.

This invention relates particularly to a dash-lamp adapted to be mounted on the dash of an automobile. More especially, the improved device is adapted to be secured 5 to an instrument-plate and a dash carrying the instrument-plate.

The primary object is to provide a dash-lamp which can be provided as a unit which is capable of being applied with great facility to an instrument-plate and dash carrying the same, without the necessity of altering the instrument-plate and dash in any way.

The invention is illustrated in its preferred embodiment in the accompanying drawing, in which—

Fig. 1 represents a broken elevational view of an automobile-dash carrying an instrument plate, the improved dash lamp being mounted thereon; Fig. 2, a broken vertical sectional view taken as indicated at line 2 of Fig. 1; Fig. 3, a rear view of the instrument-plate and instruments mounted thereon; and Fig. 4, a broken vertical sectional view illustrating the manner in which the electric connector of the dash lamp is mounted on the attaching bracket employed.

In the illustration given, A designates an automobile-dash, which ordinarily is of sheet-metal, but which may be of wood; B, an instrument-plate mounted on said dash and equipped with an ammeter B' and a switch B"; and C, the improved dash-lamp mounted on the instrument-plate B and dash A.

The dash A and instrument-plate B are of well known construction. In practice, the dash and instrument-plate are provided with registering perforations at the points 1 and 2. Ordinarily, a pair of screws, such as the screw 3, is employed to secure the instrument-plate to the dash at the points 1 and 2. In accordance with the present invention, one of the screws 3 (the upper one) is replaced by a tubular screw 4 which serves as a conduit for the passage of an electric conductor 5 which leads to the electric connector which carries the lamp-bulb.

The dash-lamp C comprises, in the illustration given, a bracket-plate 6; an electric connector 7 mounted on the bracket-plate 6; a hood 8 mounted on the forward end of the connector 7, and a lamp-bulb 9

mounted in the forward end of the connector. 55

The bracket-plate 6 has a rearwardly flanged upper portion 6^a and a wide base-portion 6^b. The flange of the portion 6^a is adapted to bear against the front surface of the dash A. The flange is extended along the lateral curved edges of the bracket-plate and the lower extremities of the flange are suitably curved, as indicated at 6^c, to bear upon the flanged edge of the instrument-plate B. The lower extremity 65 of the bracket-plate overlaps the upper portion of the instrument-plate B and is provided with a central perforation encircled by a countersunk 6^d which fits into a countersink 10 with which the instrument-plate B is provided. 70

The tubular bolt 4 has a conical portion which fits in the countersink 6^d. The bolt 4 extends through the registering perforations of the bracket-plate 6, the instrument-plate B and the dash A, and is secured by means of a nut 4^a. The lower edge of the instrument-plate is secured to the dash by means of the screw-bolt 3. 75

The connector 7 comprises a tubular shell 80 7^a whose rear end is secured in a perforation with which the bracket-plate 6 is provided; a movably mounted plug 7^b, the plug being adapted to be moved forwardly to the circuit-making position by means of a 85 stem 11 which projects laterally through a cam-slot 12 in the shell 7^a; and a coil-spring 7^c adapted to retract the plug 7^b and break the circuit.

The plug 7^b is shown fitted centrally with 90 a spring-contact 7^d. The wire, or conductor, 5 extends through the tubular bolt 4, and returns through a perforation 13 with which the back of the plate is provided. One end of the conductor is connected with the central contact 7^d. The other end is intended to be connected with one pole of the battery in any suitable manner. In the illustration given, it is shown connected with one of the terminals 14 of the ammeter, and it will 100 be understood that it will thus be connected to the battery through the ammeter connection.

The lamp-bulb 9 is shown provided with a central contact 15 adapted to make the 105 circuit when the spring-contact 7^d is in

contact therewith, as occurs when the plug 7^b is moved to its advanced position. The circuit is completed from the shell of the lamp-bulb shank to the frame of the machine and from there to the battery.

The bracket-plate 6 which carries the dash-lamp may be of a suitable design to harmonize with the design of the instrument-plate B and the instruments mounted thereon. It will be understood that the improved device may be applied by simply removing the two screws which are ordinarily employed for securing the instrument-plate to the dash, placing the dash-lamp in position on the instrument-plate, connecting the conductor 5 with a terminal of the ammeter, and then securing the dash-lamp and instrument-plate to the dash, the tubular bolt 4 being now used in place of a solid bolt 3.

The improved device can be manufactured cheaply and supplied to automobile users at a moderate price, and can be readily applied without the necessity of drilling holes in the instrument-plate and dash. Also, the dash-lamp is located in the best position to throw light upon the ammeter and switch which are mounted on the instrument-plate.

It is preferred to use a mounting for the dash-lamp which will place the lamp-bulb some distance above the instrument-plate, so that the light will be thrown upon the instruments to best advantage. However, the invention is not limited to the precise arrangement shown. The dash A is cut away at 16 to enable the instruments B' and B² to project through the dash.

The foregoing detailed description has been given for clearness of understanding only, but no unnecessary limitations should be understood therefrom, but the appended claims should be construed as broadly as permissible in view of the prior art.

What I regard as new, and desire to secure by Letters Patent, is:

1. In means of the character set forth, the combination with a motor-vehicle dash and an instrument plate adjacent the front surface thereof provided with a perforation, of a dash-lamp associated with said instrument plate and having supporting means provided with a tubular member extending through said perforation and secured to said dash, said dash-lamp having a conductor extending through said tubular member and connected with a terminal of an instrument mounted on said instrument plate.

2. In means of the character set forth, the combination with a motor-vehicle dash, an instrument plate bearing against said dash and equipped with instruments, said instrument plate being provided centrally at

its upper and lower portions with perforations, of a dash-lamp having supporting means provided with a tubular member extending through the upper perforation of said plate and connected with said dash, said dash-lamp having a conductor extending through said tubular member, and a screw extending through said lower perforation and connected with said dash.

3. The combination with a motor-vehicle dash and an instrument plate bearing against said dash, said instrument plate being provided at its upper portion with a perforation and said dash being provided with a registering perforation, of a dash-lamp having a bracket provided with a base portion conforming to and supported on the upper portion of said instrument plate and having a portion overlapping the instrument plate and provided with a perforation registering with said first-mentioned perforation, said bracket having a perforation located above the instrument plate, a tubular member extending through said perforation, and a conductor leading from the lamp through the upper perforation of the bracket and then rearwardly through said tubular member.

4. The combination with a motor-vehicle dash and an instrument plate bearing against said dash, of a dash-lamp comprising a bracket rising above the instrument plate and having a base portion resting upon the upper edge of the instrument plate and also overlapping the instrument plate, an electric connector mounted on the upper portion of said bracket, a lamp bulb carried by said connector, a conductor leading from the rear end of said connector through a perforation in said bracket above the upper edge of the instrument plate, and a tubular bolt extending through registering perforations in the bracket, instrument plate and dash, said conductor extending rearwardly through said tubular bolt.

5. A dash-lamp for the purpose set forth, comprising a bracket-plate provided at its upper portion with a perforation, an electric connector having a base portion secured in said perforation, said bracket-plate being provided at its lower portion with a screw-receiving perforation and between said connector and said last-mentioned perforation with an intermediate perforation, a tubular screw extending through said second-mentioned perforation, and a conductor extending from the rear end of said connector forwardly through said third-mentioned perforation and then rearwardly through said tubular screw.

WOLFGANG HERMANN.
